UNITED STATES PATENT OFFICE.

ERNEST A. KRONES, OF NEW YORK, N. Y., ASSIGNOR TO HIMSELF AND JULIUS D. EISENSTEIN, OF SAME PLACE.

SHIRT.

SPECIFICATION forming part of Letters Patent No. 337,341, dated March 2, 1886.

Application filed November 9, 1885. Serial No. 189,209. (No model.)

To all whom it may concern:

Be it known that I, ERNEST A. KRONES, of the city, county, and State of New York, have invented a new and useful Improvement in 5 Shirts, of which the following is a full, clear, and exact description.

Reference is to be had to the accompanying drawings, forming a part of this specification, in which similar letters of reference indicate 10 corresponding parts in both the figures.

Figure 1 is a front elevation of my improved shirt, part being broken away. Fig. 2 is a plan view of my improvement before being applied to a shirt.

15 The object of this invention is to provide shirts constructed in such a manner that the sleeves will be strengthened against the strain that comes upon them when in use.

The invention consists in the peculiar construction and arrangement of parts, as hereinafter fully described, and pointed out in the 20 claim.

A represents the body of an ordinary shirt, to which the sleeves B are secured in the usual 25 manner.

C is a re-enforcing piece, the upper end of which is widened and is sewed into the shoulder-seam that connects the sleeve B with the body A. The re-enforcing piece C extends down 30 along the sleeve B to the wristband D, and its lower end is widened to form a placket-facing, E, to face the slit at the lower end of the sleeve. Upon the upper end of the placket-facing E is

formed a tab, F, which has a button-hole, G, formed in it to receive one or the other of the 35 buttons H, secured to the re-enforcing piece C and the sleeve B, according as the sleeve is to be shortened more or less. By this construction the sleeve is strengthened throughout its entire length, and a firm support is 40 provided for the buttons H, so that the sleeve will be less liable to be torn, and will be more durable than when made in the ordinary manner.

I am aware that shirts have been made with 45 yokes extending down over the shoulder-seams and the upper parts of the sleeves, and that sleeve-placket facings have been made with tabs at their upper ends. These constructions I do not claim, broadly; but, 50

Having thus described my invention, what I claim as new, and desire to secure by Letters Patent, is—

The combination, with the body and sleeve of a shirt, of a re-enforcing strip extending down 55 along the sleeve from the shoulder-seam to the wristband, and formed at its lower end with a placket-facing for the slit at the lower end of the sleeve, and with a tab on the upper end of the placket-facing, substantially as herein 60 shown and described.

ERNEST A. KRONES.
